CLAIM

The ornamental design for a display fixture, as shown and described.

DESCRIPTION

FIG. 1 is a top, front perspective view of a display fixture showing a first embodiment of our new design;

FIG. 2 is a front view thereof;

FIG. 3 is a rear view thereof;

FIG. 4 is a right side view thereof;

FIG. 5 is a left side view thereof; and

FIG. 6 is a top view thereof.

FIG. 7 is a top, front perspective view of a display fixture showing a second embodiment of our new design;

FIG. 8 is a front view thereof;

FIG. 9 is a rear view thereof;

FIG. 10 is a right side view thereof;

FIG. 11 is a left side view thereof; and

FIG. 12 is a top view thereof.

FIG. 13 is a top, front perspective view of a display fixture showing a third embodiment of our new design;

FIG. 14 is a front view thereof;

FIG. 15 is a rear view thereof;

FIG. 16 is a right side view thereof;

FIG. 17 is a left side view thereof; and,

FIG. 18 is a top view thereof.

(Continued)

In the drawings, the broken lines depict unclaimed subject matter only. Bottom views are omitted as bottom surfaces of the display fixture are not claimed.

1 Claim, 18 Drawing Sheets
